HAIRPIN DISPENSER

Harold M. Howard, Elmhurst, Long Island, N. Y.

Application August 21, 1945, Serial No. 611,771

4 Claims. (Cl. 312—69)

1

This invention relates to hairpin dispensers and has for its object to improve generally upon a device of this kind wherein a multiplicity of hairpins may be placed as a gross supply within the device and discharged, at the will of the operator, one at a time in succession.

An object of the invention is to make practical and efficient the dispensing operation of the device in a simplification of the structure to not only facilitate the manufacture of the same but to minimize the cost thereof.

Other objects and advantages to be attained will hereinafter more fully appear in the following description.

An illustrative but non-limiting exemplification of the invention is illustrated in the accompanying drawings, wherein:

Figure 1 is a side elevation of the device;

Figure 2 is a vertical transverse section taken on or about the line 2—2 of Figure 1;

Figure 3 is a horizontal section taken on or about the line 3—3 of Figure 2;

Figure 4 is a fragmentary sectional view taken on or about the line 4—4 of Figure 3;

Figure 5 is a fragmentary top plan view; and

Figure 6 is a fragmentary section adjacent to the lower edge portion of the cover member.

Referring now to the drawings in detail, the numeral 10 designates the base portion of the device which is flattened throughout the major portion thereof and of a circular form. The base member 10 is formed, adjacent its periphery, with an upstanding flange 11 of substantial height, said flange being tapered upwardly and the taper corresponding to the normal taper of an ordinary hairpin in the set form of the latter. In the use of the device a plurality of hairpins are placed as a supply on this flanged portion 11 of the base, the pins straddling the flange in closely placed relation to each other, that is to say, the supply of hairpins is arranged in an annular series on said flange portion 11 and in abutting relation to each other. As thus placed on the flange 11, with a cover element 12 applied to the base member 10, the entire group of hairpins placed within the device are urged in one direction by a spring pressed follower element and the foremost hairpin in the circular series thereof is moved into registration with an outlet slot and has a part thereof automatically projected outwardly through the slot, thus placing the partially ejected hairpin in a position to be grasped and withdrawn from the device and at the same time the hairpin in a partially projected position arrests the movement of the remainder of the pins until the par-

tially projected hairpin is withdrawn and upon the occurrence of which the next following pin is brought into registration with the discharge slot, which operation will be described in detail as the description proceeds.

It is here noted that, for hairpins of plain straight leg members, the taper of the flange 11 may be throughout the entire height of the flange, as indicated generally to the right in Figure 2, but, to accommodate hairpins having the middle portions of their legs rebent or corrugated with the rebent portions set inwardly the inner and outer peripheral faces of the flange 11 will have recesses 13 formed therein, said recesses extending annularly throughout the entire extent of the annular upstanding flange 11 except adjacent where a vertical slot 14 is formed in the flange 11 for the ejection of the leading hairpin in the annular series thereof placed on the flange 11.

20 Also, in the region where the slot 14 is provided in the flange 11, the near portion of the flange is thickened and enlarged on its inner surface at the base thereof, said thickened portion flaring from a point approximately where the numeral 16 is applied in Figure 3. This thickened and flared portion 15 adjacent the base of the flange 11 causes a spreading of the inner leg of the hairpin inwardly as it reaches the slot 14 and this springing of the lower end portion of the inner leg of the hairpin causes the upper part of the hairpin to become projected outwardly through the slot 14 and a registering vertical slot 17 in the adjacent side wall of the cover member 12.

As shown, the upper end of the slot 17 in the cover member 12 extends a distance inwardly from the outer periphery of the side wall of the cover member, as at 18, to a point coincident with the middle of the looped upper end of the hairpin while the pin is still riding in its straddling position on the flange 11. A partially projected hairpin is indicated at 19 in Figure 2. The lower end of the slot 17 terminates a slight distance above the lower margin of the side wall of the cover member 12, as at 20. The remaining solid portion 21 below the lower end 20 of the slot 17 keeps the lower end of the outer leg of the hairpin 19 in place within the dispensing device until the hairpin is manually withdrawn through the registered slot 14 in the flange 11 and the slot 17 in the cover member 12.

It is here further noted that the bottom of the slot 14 is formed curvilinearly, as at 22, and at the inner end of the curved bottom 22 the adjacent base portion of the widened part of the flange 55 15 is notched, as at 23, said notch 23 being pro-

vided to receive the extreme lower end of the inner leg member of the hairpin 19.

Hence, as thus far generally described, the supply of hairpins grouped in touching relation to each other on the circular rack afforded by the upstanding tapered flange 11, are moved bodily and en masse until the leading hairpin 19 reaches and has its upper portion ejected outwardly through the registered flange slot 14 and side wall slot 17 of the cover member. It is therefore obvious that if the supply group of hairpins is forced bodily in the direction of the ejection slots 14 and 17 the next following hairpin moves into registration with the slots 14 and 17 and its upper portion becomes partially ejected as the preceding partially ejected hairpin is withdrawn.

Means for moving the body of hairpins to the aforesaid ejecting position will now be described.

As shown more clearly in Figures 2 and 3, an upstanding central stud 24 is provided on the base member 10. Sleeved and supported rotatably on this stud element 24 is a cylindrical hub portion 25 having an integral radial arm 26 which latter, as shown, is made as a flat strip and the same rides closely adjacent to or directly upon the inner face of the bottom member 10. Near the outer end of this arm 26 there is provided an upstanding finger piece 27 to be grasped for the purpose of moving the arm 26 in a clockwise direction as viewing the arm 26 from above as the arm is shown in Figure 3. This manual movement of the arm 26 winds a coil spring 28, one end of the spring being fastened, as at 29, to the base of the stud 24 and the outer end of the spring being fastened, as at 30, to the arm 26 adjacent the hub portion 25 thereof. In the use of the device this arm 26 is moved to a normally set position, as indicated in dotted lines, at 26', and there releasably held, in a manner to be presently more fully described, until the annular flange 11 has a supply of a multiplicity of hairpins placed thereon in straddling position. As shown, the normally releasably held position of the arm 26 is closely adjacent one side of the registered slot 14 in the flange 11 and the entire remainder of the flange may be supplied with enough hairpins to completely encircle the rack afforded by the flange 11 up to the notch 14. It is here noted that at the outer end of the arm 26, there is an upstanding extension, the lower portion 31 of which, as shown, is inclined upwardly and forwardly and thence upwardly as at 32, against the inner face of the flange 11, whence it is rebent curvedly, as at 33, over the rounded upper edge of the flange 11, and then downwardly, as at 34, where it terminates, as at 35, adjacent the upper edge of the outer annular slot 13 in the flange 11. With the rebent portions 32 and 34 of the arm 26 straddling the upper portion of the flange 11, behind the circular row of closely positioned hairpins on the rack afforded by the flange 11, and the arm 26 released to the reaction of the coiled spring 28, said arm 26 moves counterclockwise in the direction indicated by the arcuate set of arrows in Figure 3, thereby forcing the body of hairpins along the rack until the leading hairpin is moved to a position to be ejected, as shown in Figure 2, whereupon, as hereinabove stated, the leading hairpin 19 is caused to project with its upper portion outwardly through the registered slots 14 and 17.

Any suitable releasable latching means may be provided for releasably holding the spring-pressed follower arm 26 in its normally retracted position during the filling of the device with the

hairpins to be dispensed. As shown more clearly in Figures 4 and 5, a practical provision for this purpose is illustrated. In this provision, there is provided a spring catch element 35 of a peculiarly bent formation, wherein an end portion 36 is fastened in the upper end portion of a vertically disposed thickened portion 37 of the annular flange 11 adjacent where the slot 14 occurs. In this connection it is also noted that the thickened portion 37 also affords a stop shoulder for preventing the leading hairpin from passing beyond the region of the slots 14 and 17.

The spring catch element 35 is held, as just above noted, by the end portion 36 engaged in the upper end portion of the vertical thickened part 37 of the annular rack flange 11 and the outer end portion of the spring element 35 is formed with a hook, as at 38, so as to engage a stud 39 to limit the upward movement of the element 35 and the resiliency of the element 35 is such that said hooked portion 38 is normally held in engagement with said stud 39. Just above the hooked end portion 38, the element 35 is provided with an upwardly bent portion 40 constituting a shoulder to engage the arched portion 33 of the follower arm 26 so as to releasably hold the arm in its aforesaid manually retracted position against the reaction of the coil spring 28. Between the straight intermediate portion 42 of the spring element 35 where the part 33 of the follower arm 26 engages the element 35 and the supporting portion 36 of said element 35 there is an upwardly bent portion 43 somewhat higher than the aforesaid bent portion 40. This higher portion 43 of the element 35 is of such proportions that the top of the cover member 12 engages the same and depresses the latch element 35 just before the cover member is placed in its fully closed position on the base member 10. That is to say, the side wall portion of the cover member 12 is flared slightly, the angularity of the flare corresponding substantially to the tapered circumferential face of the flange 11 on the base member 10. Therefore, the cover member is applied to the base member by merely moving it downwardly axially in relation to the base member until its lower marginal portion 44 comes in contact with a peripheral shoulder 45 on the base member 10. When the edge portion 44 of the cover member contacts the flange 45 of the base member the top of the cover member 12 engaging the raised portion 43 of the latch element 35 depresses the latch element and thereby releases the retaining shoulder 40 and frees the arm 26 to the reactive effect of the coil spring 28. It is, of course, understood that the latching effect for the arm 26 is attained by merely moving the arm clockwise until the part 33 of the arm engages the latch member 35.

It is further noted that the adjacent part of the flange 11 is recessed, as at 46, for the accommodation of the latch element 35. So, too, means is also preferably provided for effecting the application of the cover 12 to the base member 11 in a definitely positioned placement of the parts. For this purpose the lower edge portion of the side wall of the cover member 12 is provided with an inturned bead 47 adapted to fit within a slightly annularly recessed portion at the base of the flange 11 of the base member 10 with but slight outward springing of the lower edge portion of the side wall of the cover member 12. In the region where the edge portion of the side wall of the cover member 12 is coincident with the aforesaid thickened portion 37 of the flange

11 the lower edge portion of the side wall of the cover member 12 is without such inturned beading 47, said non-beaded portion of the side wall constituting a recess 48 to fit over the said thickened portion 37 of the flange 11, the arrangement being such as to prevent the application of the cover until the recessed or non-beaded portion of the cover side wall is brought into registration with said thickened portion 37 of the flange. By this provision the cover is readily slipped into place on the base portion 10 and after it is in place the interlocking engagement of the recessed or non-beaded portion of the cover side wall with the base portion of the thickened part 37 of the flange 11 prevents independent rotative movement of the cover member on the base member.

15 While the cover member 12 may be plain hollow throughout, that is, as to the inner faces of its side wall and top portion, which may be continuous and uninterrupted, and annular inner wall portion 49 may be formed on and depended from its top wall, said depending annular wall being, itself, tapered in thickness, and its outer peripheral face being spaced from the adjacent inner face of the outer wall of the cover member and said parts being flared downwardly apart 20 and with the interposed portion of the flange 11 affording an effective enclosing and holding guide for the body of grouped hairpins riding on the annular rack.

25 The illustrated structure is but one exemplification of the invention and the same admits of considerable modification within the spirit and scope of the appended claims. The invention, therefore, is not limited to the specific construction and arrangement shown.

30 Having thus described the invention, what is claimed is:

1. A hairpin dispenser comprising a base member having an annular upstanding flange constituting a rack for supporting a stack of hairpins placed on the rack in straddling relation thereto and in close relation to each other, said rack having a slot at a definite place therein, spring-pressed means within the device for urging the stack of hairpins on the annular rack bodily in one direction until the leading hairpin 35 enters the slotted portion of the rack, said rack having means adjacent the slot therein for causing a protrusion of a part of the leading hairpin 40 outwardly through the slot of the rack.

5 2. A hairpin dispensing device as set forth in claim 1, wherein there is provided a cover member on the base member whereby to enclose the stack of hairpins placed on the rack for the dispensing thereof, said cover member having a slot in a wall portion thereof coincident with the slotted portion of said rack on the base member.

10 3. A hairpin dispenser comprising a circular base member having an annular upstanding flange adjacent the periphery of the base member, said flange being tapered corresponding to the flaring of the legs of the hairpin, said flange comprising a rack upon which a plurality of hairpins are placed in straddling relation thereto and closely adjacent and abutting each other in an annular stack on the rack, spring follower means for urging the stack of hairpins on the rack in one direction, said rack having a slot therein and into which slot the leading hairpin 15 is forced under pressure of the spring follower, a cover member applicable to said base member and enclosing the hairpins placed on the rack portion of the base member, said cover member having a slot therein coincident with the slot in the rack portion of the base member, and means 20 within the device for causing an outward tilting movement of the leading hairpin as the same reaches the slotted portions of the rack member and the cover member.

25 4. A hairpin dispenser as set forth in claim 3 and further including a latch means for releasably holding the spring follower means in a normally retracted position prior to the loading of the rack portion of the base with a plurality of hairpins to be dispensed, said latch means being arranged and provided so that it is moved to release the spring-pressed follower means at substantially the time the cover member is applied 30 to the base member.
